FIG. 1 is a perspective view of a storage tray for drill taps or the like showing my new design;

FIG. 2 is a top plan view thereof;

FIG. 3 is a side elevational view thereof;

FIG. 4 is an end elevational view thereof;

FIG. 5 is a sectional view taken on line 5—5 of FIG. 3; and

FIG. 6 is a sectional view taken on line 6—6 of FIG. 4.

The characteristic feature of my design resides in the combination on the storage tray disclosed of the semi-cylindrical troughs on each of the longer sides thereof disposed in the upstanding truncated supports which are separated by a pair of shallow compartments, all as shown.

I claim:

The ornamental design for a storage tray for drill taps or the like, as shown and described.
